poration, Chicago, Ill., a corporation of Dela-
ware

Original application June 11, 1931, Serial No.
543,499. Divided and this application June 20,
1935, Serial No. 27,487. In Canada July 11,
1931

21 Claims. (Cl. 146—94)

This invention relates to a new and improved slicing machine and has particular usefulness when embodied in that type of machine employed for slicing food stuffs such as bacon or 5 similar products.

This application is a division of my copending application entitled Slicing machine, Serial No. 543,499, filed June 11, 1931.

In practice, it is desirable in many instances, 10 to slice articles of food, such as bacon and the like, for packaging or other purposes, in such manner that a plurality of slices will fall together in offset relationship to provide a group of slices of predetermined number with a plurality of groups forming in succession, separated or segregated from each other. It is also desirable to have the slices in each group bear a definite and uniform offset relationship to each other.

20 The machines used heretofore are constructed to provide synchronization between feeding action of the product sliced and the rotation of the cutting blade which results in each succeeding slice falling in immediate contact with 25 the other slices and the necessity for special handling of the slices in segregating and appropriating a group of slices desired as a single portion.

Furthermore, as in the case of slicing for 30 packaging purposes, manual operations are required in order to provide the desirable offset relationship between adjacent slices of a single group.

Obviously this special handling may be accomplished in various ways but, in practice, it 35 has been customary to provide an operator at the discharge end of the machine, who collects approximately the number of slices constituting a single group or portion, in a receiving pan after 40 which the pan is quickly removed and the operation repeated.

In packaging operations, it is necessary to manually arrange each slice in a group with respect to the other slices which requires much 45 time and skill and consequent expense, and in cases where it is desirable to avoid touching the food articles with the human hands, this tedious and slow operation is performed by means of implements, such as forceps, spatula and the like, held by the operators which is even more difficult and expensive.

Accordingly, it is an important object of this 50 invention to provide a slicing machine which is entirely automatic in character and which will 55 provide by rapid operation a succession of any

desired number of slices automatically positioned in predetermined offset relationship with respect to each other to provide a group of slices and in addition provide a succession of such groups with a predetermined spacing between 5 adjacent groups.

The accomplishment of this object results in the provision of a plurality of groups of slices with spacing between each group whereby each group is segregated and presented in a manner 10 for subsequent packaging or handling purpose.

The machine of this invention comprises as three essential elements a cutting blade, an article holder and feeder, and a receiving conveyor, all of which are adapted for synchronized 15 operation to produce the desired slicing and offsetting above mentioned. In addition to the above elements, this invention includes mechanism driven in synchronism with the above named elements which is operative upon any one 20 or more of said three coating elements to alter the usual synchronized operation therebetween and to establish for a limited period a different timing relationship for producing the spacing between the groups of slices. This last- 25 named mechanism is a control mechanism and will be referred to as such in this specification.

It is contemplated that the control mechanism shall be capable of adjustment so as to provide any desired offset relationship between 30 the slices of a single group and any desired spacing between groups of any desired number of slices according to the particular type of operation practiced.

In operation, the cutting blade acts intermittently upon the article being sliced so that by altering the relationship between the rate of feed of the latter and the period of the knife the thickness of the slices may be varied.

By means of the timing device of this invention, the grouping of slices may be provided by any one of several methods. For the purpose of explanation, the article holding element and the cutting blade may be considered as a slicing unit and the conveyor as a conveying unit and it will be appreciated that any alteration between the timed relation of these two units will vary the offsetting and spacing between the slices and groups of slices received on the conveyor. Consequently, the desired grouping may be provided by either altering the relationship of the slicing unit to the conveying unit in so far as their cooperative positions are concerned or while maintaining their positions, interrupt- 40 45 50 55

ing the action of the slicing unit while permitting the normal advancement of the conveyor.

In the first alternative, the cutting unit may be bodily displaced with respect to the conveyor so as to produce a new relationship productive of the desired grouping action or the advancing movement of the conveyor may be varied such as, for instance, by momentarily increasing the speed to provide the desired space between adjacent groups while the cutting unit proceeds at the normal rate.

According to the second alternative, the slicing unit is mounted in fixed position with respect to the conveyor which is adapted to travel at a uniform rate of speed and the separation between groups of slices may be obtained by periodically interrupting the delivery of slices from the slicing unit which may include stopping the feeding action of the material to be sliced with respect to the support of the slicing unit and, in addition, producing relative movement between the rotating knife and the material to be sliced to prevent chipping of small pieces.

Consequently, the present invention, in its broadest aspect, relates to a machine entirely automatic in character which comprises as essential elements the cutting blade, the article holder and the conveyor, together with means for normally driving these coacting elements in a predetermined synchronized relationship and, in addition, a controlling mechanism which operates to alter said predetermined synchronized relationship in a desired manner to produce a space between groups of any desired number of slices with the slices of each group in a predetermined offset relationship.

Further objects and advantages of the present invention will be more readily apparent from the following description taken in connection with the embodiment of the invention shown in the accompanying drawings.

In the embodiment of the present invention illustrated in the drawings, the material is fed toward the knife by an intermittently rotatable screw shaft and in this form the means which produces the intermittent rotation of the screw shaft may be rendered periodically ineffective and simultaneously the knife bodily moved away from the material to be sliced to prevent chipping.

In the drawings which accompany this specification and made a part hereof, similar characters of reference in the several figures indicate identical parts.

Referring now to the drawings:

Figure 1 is a side view, partly in section, of the slicing machine forming the present invention.

Figure 2 is an enlarged side view of the driving end of Figure 1.

Figure 3 is a side elevational view, taken on line A—A of Figure 2.

An appropriate angle iron foundation frame 101 is provided to rigidly hold the machine in the position shown. The conveyor 92 which receives the slices from the slicing machine is shown diagrammatically as an endless belt operating over pulleys as 97. The machine parts are mounted on a frame consisting of a bed plate 102 integral with the knife end bearing truss 103 and the driving end bearing truss 104. Knife 105 is rigidly mounted on shaft 106 at 107, being held in position by appropriate means such as hub plate 108 secured to the knife by nuts 109, 110, 111 and 112. The shoulder 113 is integral with hub plate 108, and the hub is secured to the shaft 106

by nut 114. Shaft 106 is journalled in bearing 115 mounted on truss 103, and shaft 106 passes through truss 104 at 116. Shaft 106 is slidably mounted in worm wheel 117 rotatably mounted in ball bearings 118 and 119 in a manner such that the end thrusts of the worm wheel 117 are transmitted thereto. A conventional bacon clamp consisting of lower jaws 120 rigidly attached to housing 121 carrying nut 122 operated by handle 123, and upper jaws 124 integral with handle 125 mounted on shaft 126 at 127, grips product 128 between points 129 and 130 of jaws 120 and 124. Half-nut 122 rides on feed screw 131 and during the slicing operation propels the product toward the revolving knife 105. Worm wheel 117 meshes with worm 132. Worm 132 is driven by motor 133 through flexible coupling 134. Worm wheel 117 is slidably keyed to shaft 106 by key 135 and turns shaft 106. Housing 136 encloses worm wheel 117, worm 132 and bearings 118 and 119. Shaft 106 passes through cover 137 of housing 136 at 138 at which point is placed oil seal 139. Spur gear 140 is rigidly affixed to shaft 106 at 141. Gear 140 meshes with spur gear 142. Gear 142 is rotatably mounted on spindle 143 which is supported by frame lug 144. Pinion 145 is rigidly attached to gear 142. Pinion 145 meshes with spur gear 146. Spur gear 146 is rotatably mounted on spindle 147 which is supported by frame lug 148. Cam 149 is rigidly affixed to one face 150 of gear 146. Cam 149 presents a radial cam contour 151 and an axial cam contour 152. Crank arm 153 is rigidly affixed at the end 154 of shaft 106; connecting rod 155 is pivotally mounted to crank 153 through crank pin 156. Connecting rod 155 is pivotally mounted at its opposite end to pawl lever 157 by pin 158. Pawl lever 157 is rotatably mounted about feed screw 131 and carries at its opposite end pawl 159 which is pivoted on pin 160. Pin 160 is rigidly affixed to pawl lever 157. Pawl 160 cooperates with ratchet 161. Ratchet 161 is rigidly affixed to feed screw 131. Spring 162 urges pawl 159 into contact with ratchet 161. Pawl 159 carries at its opposite end roller 163, 45 pivotally mounted on pin 164 which is rigidly affixed to pawl 159. Arm 165 forms an arcuate track pivoted on pin 166. Pin 166 is rigidly affixed to plate 167. Arm 165 is provided with a fixed or integral arm 168 on the opposite end of which is rigidly affixed pin 169 upon which is rotatably mounted roller 170. Roller 170 is at all times in contact with radial cam surface 151 and is here shown in contact with segment 171 of radial cam surface 151. In this position, arm 165 contacts 55 with roller 163, disengaging pawl 159 from the ratchet 161. When the rotation of cam 151 moves segment 171 out of contact with roller 169, spring 172 withdraws arm 165 from contact with roller 163, permitting spring 162 to urge pawl 159 60 into engagement with ratchet 161. Spring 172 is rigidly affixed at one end to pin 173 which is rigidly affixed to plate 167. Spring 172 is rigidly affixed at its other end to the free end of arm 165.

As knife shaft 106 rotates in the direction of 65 the arrow, it carries pin 156 about it in a circle, which circular motion causes pawl lever 157 to oscillate about its mounting on feed screw shaft 131. Depending on the positions of arcuate track 165, pawl 159 will or will not engage ratchet wheel 70 161. Also, as knife shaft 106 rotates, it causes cam 151 to rotate through the medium of gears 146, 145, 142 and 140. It is important that the gear ratio between the speed of knife shaft 106 and cam 151 be a whole number.

Suppose cam 151 be designed on the basis of delivering nine successive slices of product followed by a dwell of five revolutions of the knife shaft during which no product is being sliced, thus giving a cycle of fourteen revolutions of the knife shaft and necessarily one cam revolution. It follows that the speed ratio between the knife shaft and the cam is 14 to 1. On this basis, segment 171 will represent five-fourteenths of 360 degrees, and it is this segment that causes roller 170 to urge arcuate track 165 into contact with pawl roller 163, preventing pawl 159 from engaging with ratchet wheel 161. During that portion of the cam revolution in which segment 171 is in contact with roller 170, no slices will be delivered by the machine. During the remaining nine-fourteenths of the revolution of cam 151, spring 172 causes arcuate track 165 to be withdrawn into the position indicated by the broken line 174. While arcuate track 165 is in position 174, slices will be delivered by the machine.

Rigidly attached to knife shaft 106 is collar 175 provided with groove 176. Yoke 177 carries pins 178 and 179 which operate in conjunction with groove 176 in collar 175. Pins 178 and 179 are rigidly mounted in yoke 177 in such a manner as to have their axes in line with each other. The yoke is mounted so that the axial line of pins 178 and 179 approximately coincides with a diameter of shaft 106. Pins 178 and 179 extend inwardly of groove 176, leaving a working clearance at the bottom of groove 176. One end of yoke 177 is pivoted on pin 180 which pin 180 is rigidly attached to bracket 181. Bracket 181 is rigidly affixed to base plate 167. The opposite end of yoke 177 carries pin 182 upon which is rotatably mounted roller 183. Roller 183 rides on the axial cam surface 152. Spring 184 is fixed at one end to yoke 177 at 185 and at the other end to cover plate 137 at 186. Spring 184 pulls the yoke 177 and its cooperating parts in the direction of cover plate 137 so that roller 183 is constantly kept in contact with axial cam surface 152.

Axial cam surface 152 presents lobe 187 which embraces an arc of nine-fourteenths of 360 degrees. When lobe 187 is in contact with roller 183, yoke 177 operating through pins 178 and 179 in grooved collar 175 on shaft 106 is holding knife 105 in the proper cutting relationship to table edge 188. After lobe 187 passes out of contact with roller 183, the roller 183 rides on the remaining five-fourteenths of the 360 degrees of axial cam surface 152, during which time knife 105 is dropped out of slicing position by the action of gravity and spring 184. This is done to minimize the tendency to produce shavings. The transition from lobe 187 to the lower section of the axial surface 152 should be accomplished in less than one knife revolution.

It is to be understood that my invention is not restricted to the specific constructions shown which are merely illustrative of the principles of my invention and many modifications may be resorted to without departing from the spirit of my invention as expressed in the appended claims.

I claim:

1. In a bacon slicing machine in combination with a main frame, means for supporting a slab of bacon and moving it forwardly in a longitudinal direction whereby normal periodic successive transverse slicing operations can be carried out thereupon, a transversely movable cutter located

at the forward portion of the machine, a longitudinally extending shaft for operating and carrying said cutter so as to effect successive transverse cutting operations, a longitudinally extending feed screw shaft having a nut member associated therewith and movable along the same, said movable nut member having means for engaging and controlling the feed of bacon slabs during the longitudinal movement thereof, a continuously rotating common operating shaft, means for continuously rotating said cutter carrying and operating shaft from said common operating shaft, means comprising reducing speed gearing for rotating the feed screw shaft from said common operating shaft but at a slower speed than the cutter carrying and operating shaft, said speed reducing gearing having associated therewith and continuously operated thereby a cam member, said slicing machine also having mechanism associated with said longitudinally extending feed screw shaft and under the control of said cam for intermittently rotating the feed screw shaft for causing a periodic cessation of the normal forward feeding movement into slab cutting position of the nut member in respect to said cutter, said slicing machine mechanism also being constructed so that it comprehends in association with said cam a member for effecting a relative shifting of the feed screw shaft and the cutter shaft at intervals whereby at the end of a series of normal cutting operations and due to said shifting movement there is effected a relative separation in a longitudinal direction as between the slab of bacon being sliced and the cutter normally operating thereupon to produce non-cutting periods at intervals.

2. In combination in a bacon slicing machine a main frame supporting a base member along which bacon slabs are fed in a forwardly longitudinal direction, a transversely operating cutter located at the forward end of the machine, a longitudinally extending cutter operating shaft for actuating said cutter in a manner to effect normal successive cutting operations as a bacon slab is fed forwardly to the cutter during the normal cutting operation, a longitudinally extending feed screw shaft, a bacon slab engaging member associated with a nut member that in turn is actuated by and from said feed screw shaft, a constantly rotating common operating shaft, means for continuously rotating the cutter operating shaft from said common operating shaft, means comprising reducing gearing and pawl and ratchet mechanism for rotating step by step said feed screw shaft from said common operating shaft but at a slower speed than said cutter operating shaft, said speed reducing gearing having associated therewith a constantly rotating cam element, a lever associated with said cutter operating shaft and said cam element for periodically moving to a non-cutting position said cutter operating shaft in a forwardly longitudinal direction and thereby moving said cutter from and ahead of its normal cutting position, said speed reducing gearing also having an associated second cam element which is operatively associated with a member of the pawl and ratchet mechanism, which second cam element normally allows said pawl and ratchet mechanism to actuate said feed screw so as to effect the step by step rotation thereof, but which second cam is constructed so as to ensure non-cutting periodic disengagement as between the pawl and ratchet.

of said pawl and ratchet mechanism whereby no step by step feeding of the feed screw takes place when the cutter occupies its non-cutting position.

3. A slicing machine wherein and whereby a slab is automatically subjected to successive series of slicing operations, said slicing machine comprising in combination and having a continuously rotating knife, a conveyor arranged to receive slices cut by the said knife, a continuous operating means for the knife, means for feeding slabs of material transversely to the plane of rotation of said knife including a feed screw, pawl and ratchet means operable from said continuous operating means and constructed and arranged for operating said screw shaft, and means operable from said continuously operating means for periodically rendering the pawl and ratchet means ineffective to interrupt the feeding movement of the slab of material towards the knife and for thereby producing a non-cutting period after each series of slicing operations.

4. In a slicing machine, a fixed support, a rotatable knife, driving means for rotating the knife, a holder for the material to be sliced slidably transversely to the plane of rotation of said knife, a screw shaft in threaded engagement with said holder, intermittently operable means operated from said driving means for rotating said shaft to advance said holder towards said knife, means operable from said driving means for periodically rendering the action of said intermittently operated means ineffective, and means actuated from said driving means for periodically moving said knife axially away from said holder.

5. In a meat slicing machine, a frame, a cutting element, a rotatable and axially movable shaft to which the cutting element is secured, means for rotating said shaft, a feed screw shaft rotatably mounted in the frame, a change speed gearing and a pawl and ratchet mechanism operatively connecting said shafts to rotate the feed screw shaft at a lower speed than the speed of rotation of said cutting element shaft, a meat slab holder slidably mounted in the frame and having threaded connection with the feed screw shaft for feed of the slab to operative position with relation to the cutting element, means including a cam member and an element pivoted on said frame to actuate said pawl and ratchet mechanism to intermittently rotate the feed screw shaft to feed the slab holder step by step to slicing position with relation to said cutting element, and means operated from said cam member and operatively connected with the cutting element shaft for periodically moving said cutting element shaft axially to move said cutting element temporarily away from and ahead of operative slicing position.

6. In a meat slicing machine, a frame, a cutting element, a rotatable and axially movable shaft to which the cutting element is secured, means for rotating said shaft, a feed screw shaft rotatably mounted in the frame, a change speed gearing and a pawl and ratchet mechanism operatively connecting said shafts to rotate the feed screw shaft at a lower speed than the speed of rotation of said cutting element shaft, a meat slab holder slidably mounted in the frame and having threaded connection with the feed screw shaft for feed of the slab to operative position with relation to the cutting element, means including a cam member and an element pivoted on said frame to actuate said pawl and ratchet mechanism to intermittently rotate the feed screw

shaft to feed the slab holder step by step to slicing position with relation to said cutting element, and means operated from said cam member and operatively connected with the cutting element shaft for periodically moving said cutting element shaft axially to move said cutting element temporarily away from and ahead of operative slicing position and subsequently operating to return the cutting element and its shaft to normal operative slicing position with relation to the meat slab.

7. In a meat slicing machine, a frame, a cutting element, a rotatable and axially movable shaft to which the cutting element is secured, means for rotating said shaft, a feed screw shaft rotatably mounted in the frame, a change speed gearing and a pawl and ratchet mechanism operatively connecting said shafts to rotate the feed screw shaft at a lower speed than the speed of rotation of said cutting element shaft, a meat slab holder slidably mounted in the frame and having threaded connection with the feed screw shaft for feed of the slab to operative position with relation to the cutting element, means including a cam member and an element pivoted on said frame to actuate said pawl and ratchet mechanism to intermittently rotate the feed screw shaft to feed the slab holder step by step to slicing position with relation to said cutting element, and means including a pivoted element having operative connection with the cutting element shaft and operatively engaged by said cam member for actuation by the latter to periodically axially move said cutting element shaft to move the cutting element out of operative slicing position with relation to the meat slab and to subsequently return said cutting element to normal operative slicing position.

8. In a meat slicing machine, a frame, a cutting element, a rotatable and axially movable shaft to which the cutting element is secured, means for rotating said shaft, a feed screw shaft rotatably mounted in the frame, a change speed gearing and a pawl and ratchet mechanism operatively connecting said shafts to rotate the feed screw shaft at a lower speed than the speed of rotation of said cutting element shaft, a meat slab holder slidably mounted in the frame and having threaded connection with the feed screw shaft for feed of the slab to operative position with relation to the cutting element, means including a cam member and an element pivoted on said frame to actuate said pawl and ratchet mechanism to intermittently rotate the feed screw shaft to feed the slab holder step by step to slicing position with relation to said cutting element, and means including a pivoted element having operative connection with the cutting element shaft and operatively engaged by said cam member for actuation by the latter to periodically axially move said cutting element shaft to move the cutting element out of operative slicing position with relation to the meat slab and to subsequently return said cutting element to normal operative slicing position, said pawl and ratchet mechanism being rendered ineffective by said pivoted member to arrest feed of the meat slab while the cutting element is out of operative slicing position.

9. In a slicing machine, a support, a shaft, a rotary cutter mounted on said shaft, means associated with said support for feeding the material to the cutter, drive means for said cutter and said feeding means, and means connected

with said drive means including cams for moving the cutter axially from and toward the cutting plane of the material fed thereto to periodically interrupt the cutting operation and for periodically interrupting said feeding means during the non-cutting periods of said cutter.

10. In a slicing machine, a support, a shaft, a rotary cutter mounted on said shaft, means including a ratchet and pawl mechanism associated with said support for intermittently feeding material to the cutter, drive means for said cutter and said feeding means, and means connected with said drive means including cams for moving the cutter axially from and toward the cutting plane of the material fed thereto to periodically interrupt the cutting operation and for periodically moving said pawl out of engagement with said ratchet to interrupt said feeding means during the non-cutting periods of said cutter.

15. 11. In a slicing machine, a support, a shaft, a rotary cutter mounted on said shaft, means including a nut and screw shaft and a ratchet and pawl mechanism associated with said support for intermittently feeding material to the cutter, drive means for said cutter and said feeding means, and means connected with said drive means including cams for moving the cutter axially from and toward the cutting plane of the material fed thereto to periodically interrupt the cutting operation and for periodically moving said pawl out of engagement with said ratchet to interrupt said feeding means during the non-cutting periods of said cutter.

20. 12. In a slicing machine, a support, a shaft axially movable in said support, a rotary cutter mounted on said shaft, means associated with said support for feeding material to the cutter, drive means for said cutter and said feeding means, and means connected with said drive means including cams, one of said cams being operably connected with said shaft to axially move said cutter from and toward the cutting plane of the material fed thereto to periodically interrupt the cutting operation and the other of said cams being operable to periodically interrupt said feeding means during the non-cutting periods of said cutter.

25. 13. In a slicing machine, a support, a shaft axially movable in said support, a rotary cutter mounted on said shaft, an arm connected to said shaft, means associated with said support for feeding material to the cutter, drive means for said cutter and said feeding means, and means connected with said drive means including cams, one of said cams being operable to engage said arm to axially move said cutter from and toward the cutting plane of the material fed thereto to periodically interrupt the cutting operation and the other of said cams being operable to periodically interrupt said feeding means during the non-cutting periods of said cutter.

30. 14. In a slicing machine, a support, a shaft axially movable in said support, a rotary cutter mounted on said shaft, an arm pivotally connected to said support and said shaft, means associated with said support for feeding material to the cutter, and means including cams connected with said drive means, one of said cams being operable to engage said arm to axially move said cutter from and toward the cutting plane of the material fed thereto to periodically interrupt the cutting operation and the other of said cams being operable to periodically inter-

rupt said feeding means during the non-cutting periods of said cutter.

35. 15. In a slicing machine, a support, a shaft axially movable in said support, a rotary cutter mounted on said shaft, an arm connected with said shaft, means including a ratchet and pawl mechanism associated with said support for intermittently feeding material to the cutter, drive means for said cutter and said feeding means, and means including cams connected with said drive means, one of said cams being operable to engage said arm to axially move said cutter from and toward the cutting plane of the material fed thereto to periodically interrupt the cutting operation and the other of said cams being operable to periodically move said pawl out of engagement with said ratchet to interrupt said feeding means during the non-cutting periods of said cutter.

40. 16. In a slicing machine, a support, a shaft axially movable in said support, a rotary cutter mounted on said shaft, an arm pivotally connected to said support and said shaft, means including a nut and screw and a ratchet and pawl mechanism associated with said support for intermittently feeding material to the cutter, drive means for said cutter and said feeding means, and means including cams connected with said drive means, one of said cams being operable to engage said arm to axially move said cutter from and toward the cutting plane of the material fed thereto to periodically interrupt the cutting operation and the other of said cams being operable to periodically move said pawl out of engagement with said ratchet to interrupt the feeding means during the non-cutting periods of said cutter.

45. 17. In a slicing machine, a support, a shaft, a rotary cutter mounted on said shaft, means associated with said support for feeding material to the cutter, drive means for said cutter and said feeding means, and means connected with said drive means including a rotary element having an axial cam surface and a radial cam surface, said axial cam surface being operable to move said cutter from and toward the cutting plane of the material fed thereto to periodically interrupt the cutting operation and said radial cam surface being operable to periodically interrupt said feeding means during the non-cutting periods of said cutter.

50. 18. In a slicing machine, a support, a shaft axially movable in said support, a rotary cutter mounted on said shaft, an arm connected with said shaft, means including a ratchet and pawl mechanism associated with said support for intermittently feeding material to the cutter, drive means for said cutter and said feeding means, and means including a rotary element having an axial cam surface and a radial cam surface connected with said drive means, said axial cam surface being operable to engage said arm to axially move said cutter shaft to move said cutter from and toward the cutting plane of the material fed thereto to periodically interrupt the cutting operation and said radial cam surface being operable to periodically move said pawl out of engagement with said ratchet to interrupt said feeding means during the non-cutting periods of said cutter.

55. 19. In a slicing machine, a support, a shaft, a rotary cutter mounted on said shaft, means including a ratchet and pawl mechanism associated with said support for feeding the material to the cutter, an arcuate-shaped track member

- 5 pivotally connected with said support operable to move said pawl out of engagement with said ratchet, drive means for said cutter and said feeding means, and means including a rotary element having an axial cam surface and a radial cam surface connected with said drive means, said axial cam surface being operable to move said cutter from and toward the cutting plane of the material fed thereto to periodically interrupt the cutting operation and the other of said cams being engageable with said track member to periodically move said pawl out of engagement with said ratchet to interrupt said feeding means during the non-cutting periods of said cutter. 10
- 10 20. In a slicing machine, a support, a shaft, a rotary cutter mounted on said shaft, means including a ratchet and pawl mechanism associated with said support for intermittently feeding material to said cutter, an arcuate-shaped track member pivotally connected with said support operable to move said pawl out of engagement with said ratchet, drive means for said cutter and said feeding means including cams, one of said cams being operable to axially move said cutter from and toward the cutting plane of the material fed thereto to periodically interrupt the cutting operation and the other of said cams being engageable with said track member to periodically move said pawl out of engagement with said ratchet to interrupt said feeding means during the non-cutting periods of said cutter. 15
- 15 20. In a slicing machine, a support, a shaft, a rotary cutter mounted on said shaft, means associated with said support for feeding the material to the cutter, means including cams for moving the cutter axially from and toward the cutting plane of the material fed thereto to periodically interrupt the cutting operation and for periodically interrupting said feeding means during the non-cutting periods of said cutter, and means for driving said cutter, said feeding means and said cams. 20

CHARLES T. WALTER.
